UNITED STATES PATENT OFFICE.

JULIUS KRAMER AND ANTON SCHMIDT, OF CHICAGO, ILLINOIS, ASSIGNEES TO PULL-MAN COUCH COMPANY, OF CHICAGO, ILLINOIS, A CORPORATION OF ILLINOIS.

SPRING SEAT.

Application filed May 27, 1918. Serial No. 236,752.

To all whom it may concern:

Be it known that we, JULIUS KRAMER and ANTON SCHMIDT, citizens of the United States of America, and residents of Chicago, 5 county of Cook, and State of Illinois, have invented certain new and useful Improvements in Spring Seats, of which the following is a specification.

This invention relates mainly to convertible seating devices, and particularly to the frame, springs and upholstering of seats, such as are employed, for instance, in rotary-seat sofa beds of the Holmes and Bostrom type, shown in U. S. Patent No. 848,305 15 where, in the main illustrative embodiment of the drawings, the yielding part is mounted within a peripheral wooden frame of rectangular shape so that the front edge is hard and unyielding.

Heretofore much attention has been devoted to the design of seats for sofa beds, but owing to the very limited depth of space available for the upholstering of such seats, especially of the rotary style, they have 25 usually been somewhat less yielding than the best practice demands. This is especially the case where the turning axis is near the center of the seat, and where the lower edge of the front panel of the seat must be high 30 enough to clear the floor in overturning the seat forwardly as required in some forms.

The main objects of this invention are to provide an improved form of rigid seat frame of shallow construction, especially in front, and to so arrange the springs and upholstering as to project well above the edges of the frame both at the sides and in front and thus provide a soft yielding seat, not only at the center but also at and including 40 the edges. Further objects are to provide an improved form of structural steel seat frame of simple design and great strength adapted for compact storage and ready assemblage of parts; and to provide an improved arrangement of and means for mounting the 45 upholstering springs.

In the accompanying drawings, Fig. 1 is a section of a sofa bed in the closed position, embodying a seat constructed in accordance 50 with the principles of this invention; Fig. 2 illustrates the same construction in open position; Fig. 3 is a plan of one corner of the metal spring part of the seat before the upholstering is applied; Fig. 4 is a detail of 55 a part of the seat frame and supporting

wires; Fig. 5 is a detail section showing the yielding front edges of the upholstered part; Fig. 6 is a side view of part of the seat and the bed bottom support; and Fig. 7 is a section taken on the line 7—7 of Fig. 6. 60

In the illustrative embodiment shown in the drawings the sofa bed as a whole comprises a relatively stationary frame 1 and a rotary seat 2 mounted turnably on and secured to frame ends 3 which are secured detachably to the back part 3', and as usual in sofa beds of the general type here shown, the seat is secured demountably in pivotal relation to the frame ends. 65

Said seat 2 is provided on its under side 70 with a foldable, sectional bed bottom 6, also constructed and arranged as customary in rotary-seat sofa beds. The usual locking device 7 is also provided for securing the seat against rotation in its bed position and for 75 securing the sections in folded relation when the device is converted to its sofa form.

The present invention relates particularly to the structure of the seat frame proper 8 which is a part of seat 2, the unhampered 80 yielding character of the cushion part which includes the springs 9 and upholstering 10 and the peculiar relation of said parts whereby a hard edge is avoided. 85

The seat frame consists mainly of a rigid 85 peripheral member including front and back rails and double end rails. The front rail is in the form of an angle bar 15 to which is secured a plate or panel 16, the upper edge of which is flush with the horizontal flange of 90 said bar, and the back rail is in the form of an angle bar 17 to which is rigidly secured a tubular support or bracket 18, the ends 18' of which extend downward and somewhat rearward to support the short middle or connecting bed section 19 pivot 20. Each of the 95 double end rails of said seat-frame consists of a pair of angle bars 21 and 22 disposed in spaced relation one above the other and secured rigidly together by means of connecting blocks or bars 23 and 24. The bar 23 is provided with a part 23' extending forward and upward when the seat is inverted for cooperation with the arms 18'' to support the middle or connecting section, as shown 100 in Fig. 6. The arm 23' has an upwardly facing notch 23'' to receive the middle section pivot. 105

The front rail 15 and panel 16 secured thereto are somewhat lower than the back 110

rail, so that the front ends of the end rails are wholly above and rest upon the front angle bar 15 and the back rail 17 is in alignment with the upper bar 21 of the end rail as shown in Fig. 1, the end rails being substantially horizontal in their seat position as here shown.

In order to support the upholstering and springs a horizontal network 27 of heavy wires is strung between the horizontal flanges on the lower side of the lower angle bars 22 of the end rails, and said network is also connected to the front angle bar 15. The rear ends of the wires extending backward from the front angle bar are bent upward and secured to the back rail 17. The plurality of coiled upholstering springs 9 are mounted upon said wire network. The upper ends of the springs are fastened together and secured in a definite relation by a heavy peripheral wire 31 or the like which is somewhat yielding; additional cross wires 32 also being carried by said peripheral wire whereby a suitable bearing is provided for the upper ends of said springs. By this construction there is provided in a most practical and durable form a yielding edge for the seat both at the front and at the sides as will be apparent from Figs. 1, 3 and 5.

The upholstering 10 is applied to the seat as shown in Fig. 1 in such manner as to provide a neat and finished appearance as will be understood. The rear edge of the upholstering is attached to the back rail 17 and the front edge extends downward over the upper peripheral wire 30 and is secured to the upper edge of the front panel 16.

The locking device 7 comprises a plurality of upright rods, the upper ends of which are bent horizontally to engage the outer rail 38 of the outer section when the bent part is swung over said rail to secure the folded relation of the sections; to release the sections the bent end is turned out of engaging position.

The operation for converting the device to a bed is as follows: The operator overturns the seat as shown in Fig. 1 by lifting the front edge and throwing it backward to the position shown in Fig. 2. The forwardly projecting handle of the lock 7 is then turned sidewise so as to release the forward section. The bed bottom is unfolded by grasping the foot-rail 38 and swinging same forward to the position shown in Fig. 2, leg 45 being swung downward into position automatically by this operation, and the inner section 6 being caused to ride upward on the lifting cam

plate 46, the short connecting section 16 being pivoted centrally on the supports 18' and 23'.

The reverse of the foregoing operation serves to convert the device back to its sofa form.

Although but one specific embodiment of this invention has been herein shown and described, it will be understood that numerous details of the construction shown may be altered or omitted without departing from the spirit of the invention as defined by the following claims.

We claim:

1. An upholstered sofa seat having a separate metal supporting frame comprising end rails, a front rail secured at the lower side of the end rails, a rear rail at the upper side of the end rail, and springs interposed between the frame and the upholstering. 75

2. A sofa seat-frame comprising a front rail and a back rail, and at each end a pair of end rails disposed one over the other, the ends of the front rail and the ends of the back rail being secured to the corresponding ends of the lower and upper end rails respectively, and means for securing each pair of end rails in fixed relation to each other. 85

3. An upholstered sofa seat having a separate rectangular metal frame including end rails, connecting front and rear rails secured at the bottom and top respectively of the end rails, and a front panel for the seat secured directly at its top to the front rail 95 and below the level of the end rails.

4. An upholstered spring sofa seat for bed davenports, comprising a separate metal frame having end rails and connecting front and rear rails, the front rail being attached 100 to the underside of the end rails, and the rear rail being attached to the upper side of the end rails leaving an unobstructed space below the rear rail and the lower level of the end rails. 105

5. The combination with an upholstered spring seat including a metal frame having end, front and rear rails, the front and rear rails being attached respectively above and below the end rails, of a front panel attached to the front rail below the lower level of the end rails, and a supporting member attached to the rear rail and offset therefrom, the attached portion being entirely above the lower level of the end rails. 110

Signed at Chicago this 24th day of May 1918.

JULIUS KRAMER.
ANTON SCHMIDT.
